UNITED STATES PATENT OFFICE.

LYNN B. WYCKOFF, OF CHICAGO, ILLINOIS, ASSIGNEE TO THE MONARCH TYPEWRITER COMPANY, OF SYRACUSE, NEW YORK, A CORPORATION OF NEW YORK.

TYPE-WRITING MACHINE.

1,022,168.

Specification of Letters Patent.

Patented Apr. 3, 1912.

Application filed September 19, 1911. Serial No. 650,102.

To all whom it may concern:

Be it known that I, LYNN B. WYCKOFF, citizen of the United States, and resident of Chicago, in the county of Cook and State 5 of Illinois, have invented certain new and useful Improvements in Type-Writing Machines, of which the following is a specification.

My invention relates to typewriting machines and more particularly to machines for preparing or "writing" stencil plates or cards, and the object of the invention, generally stated, is to provide simple and efficient means of the character specified and 15 by which stencil plates or cards may be quickly introduced into the machine and properly positioned to receive the first line of "writing", and may be introduced into and fed through the machine in a flat condition.

To the above and other ends which will hereinafter appear, my invention consists in the features of construction, combinations of devices and arrangements of parts described 25 in the following specification and particularly pointed out in the appended claims.

In the drawings wherein like reference characters indicate like parts in the various views, Figure 1 is a fragmentary, vertical, 30 fore and aft sectional view, showing the upper portion of the typewriting machine embodying my invention. Fig. 2 is a fragmentary, front elevation of the same with parts in section.

I have shown my invention in the present instance embodied in the Monarch machine and have only shown so much of said machine as may be necessary to arrive at an understanding of the invention. It should 40 be understood, however, that the invention may be embodied in various styles of typewriting machines employing a cylindrical or rotative platen.

The frame of the machine comprises corner posts 1 surmounted by a top plate 2. Fixed oppositely grooved guide rails 3 are secured by screws 4 to brackets 5 fixed to the top plate. Anti-friction balls or rollers 6 are received in the grooved faces of the 50 guide rails 3 and are also received in oppositely disposed grooved guide rails 7 of a guide bar 8 which constitutes the rear cross bar of the carriage. Forwardly projecting end bars 9 are connected to the cross bar 8 and form part of the carriage; said end bars

being provided with bearings to receive a platen shaft 10 on which a rotative cylindrical platen 11 is mounted. Upwardly extending projections 12 are formed on the end bars 9 and are apertured to receive the 60 ends of a cross bar 13 which extends throughout the length of the platen above and to the rear of the center thereof. This bar is fixed to the projections 12 and constitutes a support for sleeve-like carriers 14. Each 65 carrier is tapped to receive the threaded shank of a thumb screw 15. The end of each of the screws 15 is reduced, as indicated at 16, and is adapted to be received in a spline groove 17 which extends longitudinally in the rod 13 throughout the length thereof. It will be understood that by this arrangement the carriers are adapted to be connected against rotative movement on the rod 13 and are, nevertheless, capable of relative adjustment along the rod. Each carrier is provided with a socket which is parallel with the axis of the platen and is adapted to receive the off-set bent end 18 of a supporting arm 19. A set screw 20 is 80 received in a tapped opening in each of the carriers 14 and bears at its inner end against the end 18 of the associated supporting arm 19. From an inspection of Fig. 1 it will be seen that the supporting arms 85 19 are substantially concentric with the platen and extend forwardly and downwardly from the supporting rod 13 to a point at the front of the platen where each arm is bent inwardly, as at 21, to form a 90 bearing 22 for a feed roller 23. In the present instance each feed roller is a metallic roller with a knurled contact face or periphery 24, although other suitable feed rollers may be employed. The bent end 21 95 of each supporting arm 19 is provided with a shoulder 25 against which the associated feed roller bears at one side thereof.

At the opposite side of the feed roller is arranged a washer 26 which is maintained 100 in place against a shoulder 27 formed at the junction of the bearing portion 22 and a reduced portion of the bent end 21. The free end of the bent portion is headed at 28 to secure the washer 26 in place, and 105 prevent the detachment of the washer and associated feed roller from the supporting arm. It will be understood that the bent end 18 of each supporting arm 19 constitutes a pivot on which the arm may be turned or 110

adjusted to different set positions to bring the periphery of the feed roller nearer to or farther from the platen, and that when the set screw 20 is tightened the associated supporting arm 19 is secured against movement, to maintain the feed roller in the position to which it has been adjusted relatively to the platen. The supporting arms 19 are rigid arms and they are thus rigidly supported to rigidly support the feed rollers 23 in the positions to which they may be adjusted toward or away from the platen.

A platen scale 29 is arranged at the front of the platen beneath the printing line and may be supported from the carriage in the usual manner.

A substantially horizontally disposed stationary work-sheet supporting shelf or platform 30 is preferably formed as a part of depending arms 31 which are apertured to receive screws 32 which extend through from the rear side of the usual depending front plate 33 fixed in the usual manner to the top plate 2 of the machine. The screws 32 may be fixed to the front plate 33 by any suitable means as by lock nuts 33^a. A thumb nut 34 coöperates with each screw 32 to clamp the depending arms 31 to the forward face of the plate 33, thus fixedly securing the arms and the supporting shelf 30, which forms a part thereof, to the top plate and to the frame of the machine. The supporting shelf 30, as hereinbefore indicated, is horizontally disposed and is arranged beneath the printing line and at the front of the platen and extends longitudinally of the platen at and near the center of the machine substantially parallel with the printing line.

The supporting shelf is provided with an upwardly extending pointer 35 which is preferably formed integral therewith and projects toward and in line with the printing point, indicated at X in Fig. 2. From an inspection of Fig. 1 it will be observed that the pointer is curved in transverse section so that the side edges 35^a thereof are bent forwardly and do not form sharp edges or corners for contact with the stencil plate or card, designated as a whole by the reference numeral 36. From an inspection of the drawings it will be observed that the pointer is arranged in front of the platen scale 29 and in a position where a stencil plate may be inserted in the machine from the front of the platen and may pass between the pointer and the platen scale and be supported at its lower edge on the shelf-like support 30. The pointer, in addition to acting as such, to locate the printing point, also prevents the lower edge of the stencil plate or card from being deflected forwardly and displaced from the supporting shelf 30.

Type gears 37 are pivoted at 38 to type

bar hangers 39, secured to a segment 40. The type bars at their forward ends are supported on a type rest 41. The type bars may be actuated in the usual manner through pull links 42 and the types 43 may be of the usual construction or they may, if desired, be needle-faced types for puncturing the stencil sheet, although I prefer to employ type faces and to have the types, type bars and their actuating means of the usual construction such as that employed in the Monarch machine. It will be observed that the type bars strike upwardly and rearwardly against the front face of the platen, as indicated by the dotted line in Fig. 1.

While the invention is intended primarily for preparing stencil plates, in which case the types strike directly against the face of the stencil sheet, it should be understood that the invention may be employed for filling in cards or the like and that in such instances the usual ribbon mechanism, which is omitted in the preparation of stencil plates, may be employed.

The stencil sheet shown in the drawings is of the usual construction and comprises a thin sheet *a* and a pasteboard or a comparatively heavy paper frame or rim *b*. The margin feed rollers are off-set inwardly from the supporting arms 19, as shown in Fig. 2, and coöperate with the end portions of the frame *b*, which is usually thicker and more substantial than the stencil portion *a* of the plate. The arrangement of the parts is such that a stencil plate may be readily introduced from above and supported upon the supporting shelf 30 in substantially a flat condition in the position shown in the drawings. In this position the stencil plate is properly squared against the shelf and positioned to receive the first line of "writing." There are usually but two or three lines employed upon the stencil sheet and after the first line of the stencil is produced, the platen may be fed forward by the usual line space mechanism, not shown, to feed the stencil plate upwardly the distance of one line space, when the second line may be produced. When the card is completed it is fed upwardly and withdrawn from the machine and a new stencil plate introduced downwardly as before.

The construction, arranged in accordance with my present invention, is a simple one that affords a ready introduction and removal of the stencil sheet or card and a feeding of the stencil sheet in the machine in a flat condition and there is no necessity of effecting a release of the feeding devices in the introduction of the stencil sheets into or the removal thereof from the machine. The stencil sheets may be introduced into the machine by inserting them between the supporting arms 19 and

between the feed rollers and platen, and by effecting a reverse or backward rotation of the platen the stencil sheet will be fed downwardly until the bottom sheet thereof is brought into contact with the supporting shelf 30, which properly squares the sheet, and it is then in position to receive the impact of the types for the first line to be produced on the stencil sheet or plate.

10 Various changes may be made without departing from the spirit and scope of my invention.

What I claim as new and desire to secure by Letters Patent, is:—

15 1. In a front-strike typewriting machine, the combination of a carriage, a rotative platen carried thereby, and a stationary substantially horizontally disposed shelf-like support or platform arranged in front 20 of the platen and beneath the printing line and extending longitudinally of the platen, said support being operative to support a card or the like at the bottom edge thereof while the card is maintained in substantially 25 a flat condition in front of the platen and at the printing line.

2. In a front-strike typewriting machine, the combination of a carriage, a rotative platen carried thereby, a substantially horizontally disposed shelf-like support arranged in front of the platen and beneath the printing line and extending longitudinally of the platen, said support being operative to support a card or the like at the 30 bottom edge thereof while the card is maintained in front of the platen at the printing line, and margin feed rollers which are separate from said shelf-like support and which are supported independently thereof, 35 said margin feed rollers being coöperative with the card at the side edges thereof.

40 3. In a front-strike typewriting machine, the combination of a carriage, a rotative platen carried thereby, a stationary substantially horizontally disposed shelf-like support or platform arranged in front of the platen and beneath the printing line and extending longitudinally of the platen, said support being operative to support a 45 card or the like at the bottom edge thereof while the card is maintained in substantially a flat condition in front of the platen and at the printing line, a supporting rod arranged above the platen, supporting 50 arms which extend forwardly and downwardly from said rod, and margin feed rollers carried by supporting arms and coöperative with the side edges of the card, the arrangement being such that a card is 55 fed upwardly in front of said supporting rod.

60 4. In a front-strike typewriting machine, the combination of a carriage, a rotative platen carried thereby, and a stationary support carried by a fixed part of the ma-

chine and operative to support a card or the like at the bottom edge thereof while the card is maintained in substantially a flat condition in front of the platen and at the printing line.

70

5. In a front-strike typewriting machine, the combination of a carriage, a rotative platen carried thereby, and a support carried by a fixed part of the machine and operative to support a card or the like at the bottom edge thereof while the card is maintained in front of the platen at the printing line, said support having a card supporting surface parallel with the printing line.

75

6. In a front-strike typewriting machine, the combination of a carriage, a rotative platen carried thereby, a stationary substantially horizontally disposed supporting shelf or platform carried by the frame of the machine and arranged below the printing line and coöperative with the bottom edge of a card or the like to support it in substantially a flat condition in front of the platen and at the printing line, and margin feed rollers carried by the carriage and coöperative with the side edge portions of a card or the like at or near the printing line.

80

7. In a front-strike typewriting machine, the combination of a carriage, a rotative platen carried thereby, a substantially horizontally disposed stationary supporting shelf carried by the frame of the machine and arranged below the printing line and coöperative with the bottom edge of a card or the like to support it in front of the platen and at the printing line while the card is maintained substantially in a flat condition, margin feed rollers carried by the carriage and coöperative with the side edge portions of a card or the like at or near the printing line, means for rigidly supporting said feed rollers in place, means for adjusting said feed rollers to different set positions toward or away from the platen, and means for affording a relative adjustment between said feed rollers longitudinally of the platen.

95

8. In a front-strike typewriting machine, the combination of a carriage, a rotative platen carried thereby, a stationary substantially horizontally disposed supporting shelf carried by the frame of the machine and arranged below the printing line and coöperative with the bottom edge of a card or the like to support it substantially in a flat condition in front of the platen and at the printing line, margin feed rollers carried by the carriage and coöperative with the side edge portions of a card or the like when the same is in position at the printing line, a supporting rod arranged above the platen, supporting arms that extend forwardly and downwardly from said rod, and margin feed rollers carried by said supporting rod and coöperative with the side edges of the card at or near the printing line, the ap-

100

105

110

115

120

130

rangement being such that a card is fed upwardly in front of said rod.

9. In a front-strike typewriting machine, the combination of a carriage, a rotative platen carried thereby, a substantially horizontally disposed supporting shelf carried by the frame of the machine and arranged below the printing line and coöperative with the bottom edge of a card or the like to support it in front of the platen and at the printing line, margin feed rollers carried by the carriage and coöperative with the side edge portions of a card or the like when the same is in position at the printing line, a supporting rod arranged above the platen and having a longitudinally extending groove therein, a pair of independent carriers on said rod, a screw carried by each carrier and received in said groove to fix the carrier against rotative movement on the rod and to hold each carrier in the position to which it may be adjusted along the platen, a supporting arm pivotally mounted on each carrier, a set screw coöperative with each supporting arm to hold it in the different set positions to which it may be adjusted on its pivotal connection with the carrier, and feed rollers carried by said supporting arms.

10. In a front-strike typewriting machine, the combination of a carriage, a rotative platen carried thereby, a substantially horizontally disposed supporting shelf carried

by the frame of the machine and arranged below the printing line and coöperative with the bottom edge of a card or the like to support it in front of the platen and at the printing line, margin feed rollers carried by the carriage and coöperative with the side edge portions of a card or the like when the same is in position at the printing line, a supporting rod arranged above the platen and having a longitudinally extending groove therein, a pair of independent carriers on said rod, a screw carried by each carrier and received in said groove to fix the carrier against rotative movement on the rod and to hold each carrier in the position to which it may be adjusted along the platen, a supporting arm pivotally mounted on each carrier, a set screw coöperative with each supporting arm to hold it in the different set positions to which it may be adjusted on its pivotal connection with the carrier, and feed rollers carried by said supporting arms.

Signed at Chicago, in the county of Cook, and State of Illinois this 9 day of Sept. A. D. 1911.

LYNN B. WYCKOFF.
